JOHN J. DODGE, OF SOUTH FRAMINGHAM, MASSACHUSETTS, ASSIGNOR, BY MESNE ASSIGNMENTS, TO THE R. H. LONG MACHINERY COMPANY, OF SOUTH FRAMINGHAM, MASSACHUSETTS, A CORPORATION OF CONNECTICUT.

FEEDING DEVICE.

1,077,055.

Specification of Letters Patent. Patented Oct. 28, 1913.

Original application filed July 9, 1909, Serial No. 506,751. Divided and this application filed August 24, 1910. Serial No. 578,766.

To all whom it may concern:

Be it known that I, JOHN J. DODGE, a subject of the King of Great Britain, residing at South Framingham, in the county 5 of Middlesex and State of Massachusetts, have invented a new and useful Feeding Device, of which the following is a specification.

My invention relates to improvements in 10 machines adapted to set eyelets, and more particularly to feeding devices for such machines, and consists generally of a certain peculiarly constructed raceway and carriage therefor, together with means for supplying 15 the eyelets or causing them to be supplied to said raceway; all as hereinafter set forth.

This invention is a divisional part of the application filed by me in the United States Patent Office, July 9th, 1909, Serial No. 20 506,751, for a patent on gang eyeleting machines.

The object of my invention is to provide an eyeleting machine with a feeding device for the eyelets, which is strong and durable, 25 simple in construction, consists of few parts easily assembled, is certain in action, and withal practicable and efficient.

Other objects will appear in the course of the following description.

I attain these objects by the means and mechanism illustrated in the accompanying drawings, in which—

Figure 1 is a side elevation of a machine 35 which embodies my invention in a practical form, most of the corresponding side of the casing being omitted or cut away so as to disclose the parts within, leaving portions of the frame work and the table in section, and, Fig. 2, a rear elevation of said 40 machine, without the driving pulleys or the belt shown in the preceding view.

Similar figures refer to similar parts in the two views.

The frame or more correctly perhaps the 45 casing, which supports all and incloses some of the operating parts of the machine illustrated in the drawings, comprises side pieces 1 and 2, a base or floor piece 3 connecting such side pieces at the bottom, cross pieces 50 4 and 5 extending between said side pieces 2, lugs 6 projecting inward from each of the side pieces, and a top connection between

the side pieces from which a hood 7 projects at the front end of the casing.

9 is a work table.

At the front of the machine is a vertically-movable slide 11. A main driving shaft 12 is journaled in the cross pieces 4 and 5, and operates the slide 11 through the medium of a suitable connecting-rod 15. 55 The slide 11 carries the lower sets one of which appears at 24; and above said lower sets, in a suitable supporting member on the hood 7, are the upper, fixed sets, one of which appears at 26. A gang raceway 60 42, to coöperate with the movable sets, is fastened on a bed-plate 43 mounted on a horizontally-reciprocating carriage 44. The raceway 42, bed-plate 43, and supporting 65 part of the carriage 44 for said plate are 70 all inclined downwardly and forwardly, so that the eyelets will gravitate forward or toward the delivery end of said raceway. The bed-plate is held in place on the carriage 44 by means of a transverse rib 45 75 and two longitudinal ribs 46 on the bottom of said plate, said rib 45 engaging behind a transverse shoulder 47 on said carriage and said ribs 46 entering suitable longitudinal slots in said carriage. The 80 bed-plate is also bolted to the carriage at 48—48. Yielding stops, one of which appears at 51, are provided at the front end of the raceway 42, the office of which is to hold back the eyelets in the usual manner 85 and for the usual purpose.

Depending from each side of the carriage 44 is a pair of lugs 54 in line with the corresponding pair of lugs 6, and each pair of these lugs 54 is mounted to slide on a horizontal rod 55 fast in the aforesaid corresponding pair of lugs 6. Mounted on a stud 56, depending from the center of the carriage 44, is an anti-friction roller 57 which enters a cam-groove 58 in a cam 59 95 tight on the main shaft 12 in front of the cross piece 5. The shape of the cam groove 58 is such that, as the cam 59 revolves, the carriage 44 is reciprocated through the medium of the roller 57. The movement of the carriage 44 for the raceway 42 is so timed 100 relative to the movement of the slide 11 for the lower sets 24, that said raceway is advanced into position ready to deliver eye-

lets to said sets while the latter are down, and is withdrawn from such position as soon as said sets have risen into the eyelets directly above, so as to clear the way for the sets and the eyelets thereon as said sets continue to rise. A suitable hopper 61 for eyelets is bolted at 62—62 on the bed-plate 43 at the upper, rear end. The raceway 42 receives its supply of eyelets from the hopper 61, a rotary agitator (not shown) being employed in the hopper to assist in feeding the eyelets to said raceway, all in the usual and well-known manner.

The eyelet-agitator driving mechanism consists of a gear 63 tight on the lower terminal of a revolute agitator shaft, indicated at 127, in Fig. 1, which is journaled in the hopper 61 and the bed-plate 43, said gear being below said plate, a pinion 64 and a pulley 65 to which said pinion is attached and both of which are loose on a stud 66 projecting below said plate, two pulleys or idlers 67 on a horizontal shaft 68 mounted in an arm 69, a pulley 70 on the rear end of the shaft 12 and revolutely connected with a main driving pulley 71 loose on said shaft 12, and a belt 72 which passes under said pulley 70, over said idlers and around said pulley 65. The arm 69 extends longitudinally of the bed-plate 43, beneath the same, carries the shaft 68 at its rear end, and has its front end pivoted at 73 to the carriage 44; and said arm is supported back of its pivotal point on an eccentric or cam 74 tight on a stem 75 journaled in two lugs 76 rising from said carriage at the rear end. The stem 75 extends from the lugs 76 out beyond the side 1, and has a handle 77 on its outer end to facilitate turning the same. The pulley 70 is held in place on the shaft 12 by a washer 78 and a bolt 79, the latter being tapped into the rear end of said shaft, and said pulley is rotatably connected with the pulley 71 by a pin 80 which projects from the inner face of said pulley 70 into said pulley 71. The pulley 71 is belted to a main or counter-shaft (not shown) and revolves during the entire time that the machine is in use, hence the agitator-driving mechanism described above revolves constantly and keeps the eyelets in the hopper 61 in a continual state of agitation so that a full supply of eyelets is insured to the raceway 42. The proper tension is put on the belt 72 by turning the stem 75 and its cam 74 to swing the arm 69 up or down on its pivot 73, said belt being tightened or loosened accordingly as the result of such action, since the distance between the axes of said pivot 73 and the shaft 68 is always the same regardless of the position of said arm, while the distance between the axes of said shaft and the shaft 12 changes when the arm moves. A suitable clutch, or clutch mechanism such as that disclosed in my

aforesaid application, also in another divisional application filed on even date herewith, and serially numbered 578,767, is employed to rotatably connect the shaft 12 with the pulley 71 and disconnect it therefrom, it not being desired to operate the movable sets and the raceway continuously.

The operation of the machine herein shown, so far as the present invention is concerned, will be fully understood from the preceding description and needs no further explanation.

The manner in which the bed-plate 43 is mounted on the carriage 44 enables me easily and quickly to remove the raceway 42 together with the hopper 61 from the machine, when for any reason it becomes necessary or desirable to do so, by simply removing the bolts 48 and lifting said plate from said carriage, after first disengaging or disconnecting the belt 72; and the members can be as readily reunited. The relative positions of the carrying members for the belt 72 are such that said belt and its operation are not materially affected by the reciprocating movement of the carriage 44.

More or less structural and other changes may be made in my invention without departing from the nature thereof.

What I claim as my invention, and desire to secure by Letters Patent, is—

1. The combination, in an eyeleting machine, with a reciprocating carriage having an inclined top, of a raceway provided with a bed-plate removably mounted on said inclined top of the carriage, transverse engaging projections on said carriage and plate to hold the latter against endwise displacement in a forward direction, longitudinal engaging means, comprising a rib and groove, between said carriage and plate to hold the latter against lateral displacement, and additional fastening means, which are removable, to clamp the plate to the carriage.

2. The combination, in an eyeleting machine, of a reciprocating carriage, agitator-actuating mechanism supported by said carriage, such mechanism including a pulley, an arm attached at one end to and movable with said carriage and extending rearwardly therefrom, idlers supported at the back end of said arm, a driving pulley, and a belt passing around said pulleys and over said idlers.

3. The combination, in an eyeleting machine, with a frame or casing, a shaft journaled in such casing, and a pulley on such shaft, of a carriage slidably mounted in said casing, a raceway and a hopper supported by said carriage, agitator-actuating mechanism consisting in part of a shaft extending below said hopper and a gear on said shaft, a pulley provided with a pinion to mesh with said gear, such pulley and pinion being mounted on a stud also supported

by the carriage, an arm attached at one end to the carriage and extending rearwardly therefrom, idlers supported at the back end of said arm, and a belt passing around said pulleys and over said idlers.

4. The combination, in an eyeleting machine, of a reciprocating carriage, agitator-actuating mechanism supported by said carriage, such mechanism including a pulley, 10 an arm pivotally attached at one end to and movable with said carriage and extending rearwardly therefrom, idlers supported at the back end of said arm, a driving pulley, a belt passing around said pulleys and over 15 said idlers, and means to adjust said arm on its pivot.

5. The combination, in an eyeleting machine, with a frame or casing, a shaft journaled in such casing, and a pulley on such 20 shaft, of a carriage slidably mounted in said casing, a raceway and a hopper supported by said carriage, agitator-actuating mechanism consisting in part of a shaft extending below said hopper and a gear on 25 said shaft, a pulley provided with a pinion to mesh with said gear, such pulley and pinion being mounted on a stud also supported by the carriage, an arm pivotally attached at one end to the carriage and extending rear- 30 wardly therefrom, idlers supported at the

back end of said arm, a belt passing around said pulleys and over said idlers, and means to adjust said arm on its pivot.

6. The combination, in an eyeleting machine, of a movable carriage, agitator-actuating mechanism supported by said carriage, such mechanism including a pulley, an arm attached at one end to said carriage and extending rearwardly therefrom, an adjusting cam mounted on said carriage in supporting 35 relation to said arm, idlers supported at the back end of said arm, a driving pulley, and a belt passing around said pulleys and over 40 said idlers.

7. In an eyeleting machine, the combination of a pair of slideway members, a driving shaft extending parallel with the members and in a plane centrally between them, a wheel on the shaft having a cam groove 45 in its periphery, a raceway carriage slidable 50 on the said members, and means fixed on and carried by the carriage and extending therefrom between the said members and into the cam groove for reciprocating the carriage by the wheel.
